UNITED STATES PATENT OFFICE

166,382

COMBINED FENCE AND GATE

Joseph A. Falatico, Baltimore, Md.

Application June 21, 1949, Serial No. 3,440

Term of patent 14 years

(Cl. D28—1)

To all whom it may concern:

Be it known that I, Joseph A. Falatico, a citizen of the United States, residing at the city of Baltimore, State of Maryland, have invented a new, original, and ornamental Design for a Combined Fence and Gate, of which the following is a specification, reference being had to the accompanying drawing, forming a part thereof, and wherein:

The figure is an elevational view of a combined fence and gate, showing my new design.

I claim:

The ornamental design for a combined fence and gate, substantially as shown.

JOSEPH A. FALATICO.
